CARROLL H. DUNNING, OF LOS ANGELES, CALIFORNIA, ASSIGNOR TO DUNNING PROCESS COMPANY, A CORPORATION OF CALIFORNIA

METHOD AND MEANS OF PRODUCING COMPOSITE PHOTOGRAPHS WITH SOUND ACCOMPANIMENT

Application filed October 1, 1928. Serial No. 309,692.

This invention relates to photography, and particularly to that type of photography having a sound accompaniment. At the present time, so-called talking moving pictures are being exhibited at different theatres throughout the country. Talking moving pictures present quite a problem in that the actors must perform in a room which is sound-proof in order that extraneous sounds should not be introduced into the recording apparatus. Difficulties, however, are often encountered, particularly if the so-called scenes require different locations in which case so-called trick photography must be introduced. Ordinarily in the so-called talking moving picture, the film itself carries a sound wave and this sound wave actuates certain electrical responsive apparatus which affects an amplifying arrangement and loud speaker, so that the audience hears certain sound, either talking, the roar of cannons, motors, and the like, during the progress of the picture. If, for instance, a given scene were to be depicted such as a fortress and observers in a balloon above said fortress, it would be readily realized that the production of the so-called talking picture for such a situation would be difficult of accomplishment.

The present invention presents a novel and useful method of being able to photographically record such a scene along with any accompaniment desired, whether it be voice, music, gun-fire, or the like, under the direct control of the producer of such a picture and without extraneous sounds other than the sounds desired being present.

The invention contemplates objects other than those above mentioned, which permit a photographing of several situations or actions in an inexpensive manner and one that will produce superior results which can be ascertained in advance of actual photographing.

Primarily my invention contemplates the production of composite photographs with

sound accompaniment, by producing separately one of the component portions of said photograph followed by photographing a second component portion simultaneously with the recording of sound accompaniment, then combining the separate components together with the sound accompaniment. However, I do not desire to confine myself to any specific method of producing or combining the component portions. The composite photograph may be made by any of the present practice methods, such as the traveling mat or protective action silhouette in conjunction with a background scene, or by interposing an opaque portion while photographing another portion of a composite photograph, simultaneously with the recording of sound accompaniment.

The above methods are only by way of example, as other means may be utilized by any one skilled in the art.

The production of sound accompaniment is at present only accomplished in studios equipped for this purpose and therefore it is exceedingly difficult and expensive if not in fact impossible to photograph actors at inaccessible locations with synchronous sound accompaniment. In the example first given wherein a balloon was above a fortress, it is possible by my invention not only to introduce into said scene a dialogue depicting a conversation between the observers in the balloon, but likewise introduce scenes of distant gunfire or martial airs, presumably coming from the fortress. Of course, either one or the other of such sounds may be eliminated as desired.

In carrying out my improved method reference is made in the first instance to United States Letters Patent for method of producing composite photographs, issued January 4, 1927, No. 1,613,163, which patent describes in detail a method of composite photography wherein the action is adapted to be placed upon certain scenes without phantom. The

method described in this patent may be utilized in carrying out an embodiment of the present invention. However, I describe a given method which has given excellent results where sound accompaniment is utilized. 5 This method consists in the following, assuming that I intend to utilize a fortress scene with a captive balloon thereabove, as before mentioned, I will first describe one 10 method of producing a transparency, also called a transparent member of the fortress: I first take a negative of the fortress scene which may have been made from an actual setting, a miniature, or an illustration. 15 From this negative, I print a positive on one side of an unexposed double coated film. By double coated film, I mean any light sensitive film having an emulsion on both sides or two single coated films which when together have 20 two light sensitive surfaces. I develop and fix this positive without exposing the other side. Then I pass light through the finished positive, thus producing a negative exposure of the given scene on the other side of 25 the double coated film. I then dye tone the positive side a certain color, such as orange, and the negative side I dye tone some neutral shade, such as bluish gray. These two dye 30 toned images are so balanced as to have the same photographic value to approximate white light. The dye toning consists in replacing the exposed silver salts with some chemical of a certain color on the positive side and some chemical of a neutral shade 35 on the negative side. These operations can be reversed by starting with a positive of the fortress scene instead of a negative.

The transparent member containing the previously prepared fortress scene is now 40 placed forwardly of an unexposed panchromatic film, and the second scene (in this case, the men in the balloon basket) is illuminated with light to which the transparent member is uniformly transparent. The background 45 of the second scene is simultaneously illuminated evenly with light approximately complementary in color to the color of the positive side of the transparent member. Then the transparent member and the sec- 50 ond scene are exposed simultaneously to the unexposed panchromatic film and simultaneously with the recording of the dialogue of the men in the balloon basket. Sound effects presumably coming from the distant fortress 55 scene, or elsewhere, may be interpolated simultaneously with the recording of the dialogue, or may be combined with the sound recording at another time.

The method is illustrated in the accom- 60 panying drawing, wherein the figure is a dia- grammatic view showing one manner of pro- ducing a composite picture with sound ac- companiment in accordance with the inven- tion.

65 In the drawing, the transparent member

or film containing the first component or background action of the composite picture to be produced is designated as *a*, the panchromatic film or composite picture negative is designated as *b*, the foreground action is designated as *c* and the background of the second scene or foreground action is designated as *d*. The camera through which the negative *b* and the transparent member pass is designated as *e* and is illustrated as comprising sound recording means *f* which is connected with a microphone *g* located in proximity to the foreground action *c*, which action and the background *d* thereof are illuminated by means designated as *h*. 75

It is not departing from the spirit of my invention to expose the fortress negative to one side of the double coated stock and a positive of the fortress scene to the other side of the double coated stock and develop 85 and fix the two images at the same time; and afterward dye tone the two images as before described.

If there is no appreciable movement in the fortress scene, I can produce it on a sta- 90 tionary glass or other transparent material by painting or photography.

Any previously prepared transparent member containing a component portion of a composite photograph, may be interposed 95 between the basket scene and the unexposed panchromatic film, so long as it is uniformly transparent photographically to the illumi- nation on the balloon basket scene and selec- tively transparent photographically to the 100 background illumination of the basket scene.

The reason for coloring the background and the action just depicted has been set forth in the patent above mentioned.

I have not described herein any particular 105 method of recording the sound, it being ob- vious that individual producers will have in- dividual methods for this purpose, but I have provided a ready means whereby such sound can be produced in accordance with the 110 scenes depicted.

Having thus disclosed my invention, what 115 I claim and desire to secure by Letters Pat- ent is:

In the production of a motion picture com- 120 prising two components, the method of con- trolling the various sounds related to each component, which includes photographing the first component without sound, making a positive colored transparency therefrom 125 whose shadows will pass light of approxi- mately their own color and whose high lights will pass either neutral or complementary light; placing said transparency forwardly 130 of an unexposed negative; making a com- posite photographic record on the unexposed negative by photographing the second com- ponent through the positive transparency of the first component by illuminating the sec- 135 ond component with a light that will pass

uniformly through both high lights and shadows of the transparency and by illuminating the background of the second component with a light that will pass through the high lights but not the shadows of the transparency; simultaneously recording the desired synchronous sounds of the second component, and combining sound and composite picture record into one synchronous unit.

In testimony whereof I have signed my name to this specification at Los Angeles, California, this 24th day of September, 1928.

CARROLL H. DUNNING.
